**COVER FASTENING FLEXIBLE LUG ASSEMBLY
FOR DRUMS**

Charles A. Uncapher, Chicago, Ill., assignor to Continental Can Company, Inc., New York, N.Y., a corporation of New York

Filed Oct. 8, 1962, Ser. No. 228,904

5 Claims. (Cl. 229—47)

This invention relates to an improved container, cover and fastening lug assembly and, in particular, to an improved fastening lug assembly providing a novel relationship between the cover and the container when the cover is either loosely mounted upon or securely fastened to the container.

An object of this invention is to provide an improved fastening lug assembly constructed to facilitate engagement and disengagement thereof with a container cover.

Another object of this invention is the construction of a fastening lug assembly which is contoured to the configuration of an associated cover.

A further object of the invention is the formation of a resilient fastening lug assembly having a spring-type pilot flange adapted to snap over the cover when the cover is placed upon the container, or in the event no cover is provided with the container, to overlie the upper edge of the container.

Another object of the invention is the provision of a resilient fastening lug assembly made from a single elongated piece of sheet material having a slot in an intermediate portion thereof which performs the dual function of providing a flexible hinge zone whereby the fastener lug assembly may be used with covers of various depths and peripheral curl configurations; the slot also providing a recess for the reception of a tool to securely position the cover upon the container.

Still another object of this invention is the relative dimensioning of the slot and a cover skirt to provide a fulcrum point whereby a tool may be used as a lever of the first class to enable an incompletely seated cover to be completely seated on the container simultaneously with the fastening of the cover upon the container.

Another object of the invention is to secure the fastening lug assembly to the container by a plurality of struck-out, deformable tangs, the majority of which are deformed in a direction to counteract the force created by a tool when the cover is being secured upon the container.

A further object of the invention is to contour the fastening lug assembly to the configuration of the container body to prevent damage, distortion or loss of the fastening lug assembly when the container is shipped without a cover.

Another object of the invention is the configuration of the container cover to prevent damage, distortion or loss of the fastening lug assembly when the container is shipped with a cover temporarily seated thereon.

Another object of the invention is the provision of a novel method of simultaneously seating an unseated cover upon a container and automatically locking the seated cover in place.

With the above, and other objects in view that will hereinafter appear, the nature of the invention will be more clearly understood by reference to the following detailed description, the appended claims and the several views illustrated in the accompanying drawings.

In the drawings:

FIGURE 1 is a fragmentary top perspective view of a container, a cover, and a plurality of fastening lug assemblies in accordance with this invention, and shows the cover secured to the container by a plurality of the fastening lug assemblies.

FIGURE 2 is a fragmentary enlarged cross-sectional

2

view of the container, cover and one of the fastening lug assemblies taken along line 2—2 of FIGURE 1 and illustrates the relationship between the various components in accordance with one form of the invention.

FIGURE 3 is an enlarged perspective elevational view of one of the fastening lug assemblies illustrated in FIGURES 1 and 2 prior to the attachment of the fastening lug assembly to a container.

FIGURE 4 is an enlarged fragmentary side elevational view of the container, cover and fastening lug assembly of FIGURES 1 and 2, illustrating the cover temporarily positioned atop both the container and the fastening lug assembly.

FIGURE 5 is an enlarged fragmentary cross-sectional view taken along 5—5 of FIGURE 4 showing the cover temporarily seated upon the container; the cover being contoured to the configuration of an upper portion of the fastening lug assembly to prevent damage to the fastening lug assembly upon shipment of the container.

FIGURE 6 is an enlarged fragmentary cross-sectional view of a container, a cover and fastening lug assembly similar to that illustrated in FIGURE 2 but showing a modified form of cover and fastening lug assembly, the fastening lug assembly securing the cover upon the container.

FIGURE 7 is an enlarged fragmentary cross-sectional view of a container, a cover, and a fastening lug assembly similar to that illustrated in FIGURES 1 and 2, but showing an alternative cover, unseated with respect to the container, and a tool in position preparatory to its use for simultaneously seating the cover upon the container and fastening the cover thereto.

FIGURE 8 is an enlarged fragmentary cross-sectional view similar to FIGURE 7 and illustrates the cover completely seated upon the container and in phantom lines, the tool positioned preparatory to crimping a portion of the fastening lug assembly to the configuration of the cover.

FIGURE 9 is an enlarged fragmentary cross-sectional view illustrating the structure of FIGURES 7 and 8 in the final assembled form.

This invention is particularly suited for use with containers such as fiber drums which are used to transport both bulk and viscous material. Such fiber drums are usually shipped to the packer with the covers removed or only temporarily secured thereto. In either case, upon filling the drums or containers with the particular fill involved, the covers are placed upon and secured to the containers by a plurality of fastening lug assemblies.

Referring to the drawings in detail, FIGURES 1 and 2 illustrate a container or fiber drum 10 having a container body 11. The container body 11 includes inner and outer peripheral wall surfaces, 12 and 13, respectively, and an upper edge 14.

A cover 15 is seated upon the upper edge 14 of the container body 11. While different types of covers may be used in the practice of this invention, cover 15 is provided with an end 16 sloping gradually radially outwardly, downwardly and then upwardly to form an upwardly facing annular snap flange receiving shoulder 17. A lowermost portion 18 of the snap-flange receiving shoulder 17 is in substantially the same horizontal plane as the upper edge 14 of the container body 11. The upwardly sloping portion of the snap-flange shoulder 17 is joined to a cover bead 20 which seats upon the container upper edge 14. A cover rim or skirt 21 is integrally connected to the bead 20 and depends peripherally downwardly therefrom in partial abutting relationship with the external container wall surface 13. The lowermost portion of the rim or skirt 21 terminates in an external curl 22.

A fastening lug assembly, prior to attachment to the container 10, is best illustrated in FIGURE 3 and is gen-

erally designated by the numeral 23. The fastening lug assembly 23 consists of an elongated flexible sheet material body 24. The fastening lug assembly body 24 comprises three basic portions; a bottom container attached portion 25, an intermediate hinge zone portion 26 and a top pilot flange portion 27.

The bottom container-attached portion 25 includes a pair of identical rounded corners 45. Three triangular shaped tangs 28, 29 and 30 are struck out in longitudinal alignment along the central axis of the sheet material body 24, creating a plurality of respective apertures 31, 32 and 33. The tangs 28 and 30 are bent upwardly while the tang 29 is bent downwardly (see FIGURE 2), but all three of the above-mentioned tangs are struck from the body 24 in a direction normal to the longitudinal extent of the sheet metal body 24. Ends 34, 35 and 36 of the respective tangs 28, 29 and 30 are pointed to facilitate piercing of the container body 11 and upon subsequent deformation (see FIGURE 2), positively secure the fastening lug assembly 23 upon the container 10.

The intermediate hinge zone portion 26 is weakened by the provision of an elongated, longitudinally extending slot 37, bounded by a pair of longitudinally extending side walls 38 and 40, and a pair of upper and lower transverse, arcuate walls 41 and 42, respectively. The upper arcuate wall 41 includes an outer arcuate tool bearing edge 43 (see FIGURE 2), for a purpose to be hereinafter disclosed. At each side of the elongated slot 37 there is an integral hinge or rib strip 44. The hinge strips 44 constitute a variable hinge zone area defined or limited in longitudinal extent by the upper and lower arcuate walls 41 and 42, respectively. That is, the hinge strips 44 may readily be transversely bent, deformed or hinged at any point along their longitudinal extent between the arcuate walls 41 and 42.

The top pilot flange portion 27 of the fastening lug assembly 23 includes an integral, solid, upper connecting portion 46, a downwardly opening cover bead receiving channel 47 and an upwardly and outwardly flared pilot snap-flange 48. As is best illustrated in FIGURES 1 and 2, an inner bead receiving channel surface 50 and a pilot snap-flange surface 51 of the top pilot flange portion 27 are contoured to matingly seat upon the respective cover bead 20 and snap-flange receiving shoulder 17.

In use, a plurality of the fastening lug assemblies 23 are secured circumferentially about the container body 11 adjacent the upper edge 14. The tang ends 34, 35 and 36 are deformed to abut against the inner container wall 12 and thus the entire fastening lug assemblies 23 are maintained in abutting relationship to the outer container wall 13.

After the fastening lug assemblies 23 have been secured to the container 10, the container may be shipped to a packer with the cover 15 either removed or loosely seated upon the container, as is best illustrated in FIGURE 5. Due to the mating configuration between the cover 15 and the top pilot flange portion 27, each fastening lug assembly 23 is protected against damage, distortion or loss. The cover 15, illustrated in FIGURES 5 and 6, is loosely mounted on the container body 11 and overlies the fastening lug assembly 23. The cover curl 22 traverses the slot 37 substantially medially thereof to reinforce the intermediate hinge zone portion 26, as well as the top pilot flange portion 27 should the container be abused during shipment.

To pack and close the container 10, the loosely mounted cover 15 illustrated in FIGURE 5 is removed, a desired fill placed in the container 10 and the cover placed upon the container between the fastening lug assemblies 23 and the outer container wall 13.

FIGURES 7 through 9 illustrate the successive steps in permanently securing a container cover 55 to the container. The cover 55 shown in FIGURES 7 through 9 is a variation of the cover 15 differing only in the depth of a snap-flange receiving shoulder 57. The cover 55

has a bead 60, a rim or skirt 61 and a peripheral curl 62.

More often than not, when a cover is initially placed upon a container, it is not completely seated upon the container upper edge. This condition appears in FIGURE 7 wherein the unseated cover bead 60 is illustrated in vertically spaced relation to the upper edge 14 of the container 10. To assure the effective closure of the unseated cover 55, the slot 37 of the fastening lug assembly 23 has been novelly created to cooperate with the cover curl 62 to assure the simultaneous seating and securing of the cover 55 upon the container 10.

As the cover 55 descends along the external wall 13 of the container 10, the curl 62 hinges, deforms or bends the fastening lug assembly 23 outwardly at the intermediate hinge zone portion 26, defined by the longitudinal extent of the slot 37, to create a tool receiving recess 63. A tool 64, which may be a screwdriver or the like, is inserted through the upper portion of the slot 37 into the tool receiving recess 63 and contacts the cover 55 at the junction of the rim or skirt 61 and the edge of the curl 62. Upon pivoting the tool 64 in the direction of the arrow in FIGURE 7, a lever of the first class is created, the fulcrum of which is at the tool bearing edge 43 of the slot 37. By pivoting the tool from the position illustrated in FIGURE 7 to the position shown in FIGURE 8, the cover 55 is seated upon the container upper edge 14 and is simultaneously secured thereto by the bead receiving channel 50 snapping over the cover bead 60 (FIGURE 8). Also, the upwardly deformed tangs 29 (FIGURE 2) and 30 provide maximum counteracting force to the force created by the pivoting tool 64 and the tendency of the fastening lug assembly 23 to pull away from the container body 10 is prevented.

Once the container 10, cover 55, and fastening lug assembly 23 are in the position illustrated in FIGURE 8, the tool 64 may be withdrawn from the tool receiving recess 63 and positioned against the pilot snap-flange 48, as is illustrated in phantom lines in FIGURE 8, preparatory to crimping the pilot snap-flange 48 to the contour of the cover 55. The completely secured assembly is illustrated in FIGURE 9.

The steps employed in securing the components illustrated in FIGURES 7 through 9 in assembled relationship are equally applicable to the assembly of FIGURES 1 and 2 with the exception that the pilot snap-flange 48, illustrated in the latter figures, is not crimped by the tool 64.

FIGURE 6 illustrates the versatility of the fastening lug assembly of this invention. Another cover 65 of conventional construction comprises a snap-flange receiving shoulder 66, a bead 67 and a skirt or rim 68. The skirt or rim 68 terminates in an outwardly, upwardly directed hem 70 of substantial length. A hem shoulder 71 is disposed above the upper arcuate wall 41 of a fastening lug assembly 72, which is identical with the fastening lug assembly 21 with the exception that the pilot snap-flange may be upturned abruptly as at 73. Even though the skirt or rim 68 terminates well above the intermediate hinge zone portion 26 the hinge zone portion 26 still readily hinges, bends or deforms to accommodate the hem 70.

Thus, the fastening lug assembly of this invention may be used with covers having rims or skirts of different depths and diverse peripheral curl configurations. The fastening lug assembly is not limited to a specific size or style of cover, but may be employed, without modification to secure diverse existing covers and containers in assembled relationship.

While a preferred form of container cover and fastening lug assembly and a preferred method of assembly the same is disclosed in detail herein, it is to be understood that variations in the disclosure of these method steps and part arrangements may be provided without departing from the scope of the invention and defined in the appended claims.

I claim:

1. A container, cover and fastening lug assembly wherein the cover is secured to the container upper end and includes a bead and a downwardly directed rim terminating in a reinforced peripheral edge, said fastening lug including an elongated body having a bottom container attached portion, an intermediate hinge portion and a top lug portion, said intermediate hinge portion including an elongated weakened area defining an elongated hinge zone disposed between the bottom container attached portion and the top lug portion and within the confines of which the lug may be selectively hinged, whereby the top lug portion is seated upon the cover bead irrespective of the downwardly directed rim length and the configuration of the peripheral edge, said elongated weakened area being an elongated slot of a length extending substantially from the bottom container attaching portion to the top lug portion.

2. The container, cover and fastening lug assembly of claim 1, wherein the slot is defined by a plurality of elongated spaced hinge strips.

3. The container, cover and fastening lug assembly of claim 1, wherein the container cover and rim overlie the top lug portion of the fastening lug assembly to preclude damage, distortion or loss of the fastening lug assembly when the container is shipped with a cover temporarily thereon.

5 4. A fastening lug assembly comprising an elongated body having a bottom container attaching portion, an intermediate hinge portion and a top lug portion, said intermediate hinge portion defining an elongated hinge zone disposed lengthwise of said fastening lug between the bottom container attaching portion and the top lug portion and within the confines of which the lug may be selectively hinged at any one of a plurality of selected positions along the length of said hinge zone thereby adapting the fastening lug assembly for use with diverse covers and containers, said elongated hinge zone including a weakened area defined by an elongated slot of a length extending substantially from the bottom container attaching portion to the top lug portion.

10 15 5. The fastening lug assembly of claim 4, wherein the slot is defined by a plurality of elongated spaced hinge strips.
